[57] CLAIM

The ornamental design for a binocular, substantially as shown and described.

DESCRIPTION

FIG. 1 is a top perspective view of a binocular showing my design;

FIG. 2 is a top plan view;

FIG. 3 is a bottom plan view;

FIG. 4 is a right side elevational view, and the left side elevational view thereof is a mirror image;

FIG. 5 is a front elevational view of the eyepiece end thereof; and

FIG. 6 is a rear elevational view thereof.

The surface treatment pattern which is shown in part for convenience of illustration on the central body portion of the binoculars is understood to cover the entire area now shown only in part.

*Fig. 2.**Fig. 3.**Fig. 4.**Fig. 5.**Fig. 6.*
